CLAIM

The ornamental design for an aroma device, as shown and
described.

DESCRIPTION

FIG. 1 is an exploded perspective view of an aroma device;
FIG. 2 is a front view thereof;
FIG. 3 is a left side view thereof;
FIG. 4 is a rear view thereof;
FIG. 5 is a right side view thereof;
FIG. 6 is a top view thereof; and,
FIG. 7 is a bottom view thereof.

The broken lines shown in the figures are for the purpose of
illustrating portions of the aroma device and form no part of
the claimed design.

1 Claim, 7 Drawing Sheets
